UNITED STATES PATENT OFFICE.

GEORGE A. WEBER, OF NEW YORK, N. Y., ASSIGNOR TO THE WEBER RAILWAY JOINT MANUFACTURING COMPANY, OF NEW YORK, N. Y., A CORPORATION OF WEST VIRGINIA.

RAIL-FASTENING.

SPECIFICATION forming part of Letters Patent No. 739,465, dated September 22, 1903.

Application filed October 9, 1902. Serial No. 126,605. (No model.)

To all whom it may concern:

Be it known that I, GEORGE A. WEBER, a citizen of the United States, and a resident of the borough of Manhattan, in the city, county, and State of New York, have invented certain new and useful Improvements in Rail Fastenings, of which the following is a specification, accompanied by drawings.

My invention relates to rail-fastenings for railroads; and its objects are to improve upon such fastenings and enable the rail to be adjusted both longitudinally and laterally, while at the same time affording a secure fastening for the rail.

Further objects of my invention will hereinafter appear; and to these ends my invention consists in a rail-fastening for carrying out the above objects constructed and arranged and having the general mode of operation substantially as described in this specification and shown in the accompanying drawings, in which—

Figure 1 is a top plan view of a rail-fastening embodying my invention; and Fig. 2 is an end view of the same, partly in section. Fig. 3 is an end view, partly in section, of a modification.

According to my invention the rail is secured to the tie by means of a construction which permits vertical adjustment of the rail and also horizontal adjustment both longitudinally and laterally, while at the same time the rail is held securely to the tie and lateral support is afforded for the web of the rail to effectually prevent the rails from spreading.

Referring to the drawings, and more particularly to Figs. 1 and 2, A represents a portion of a tie or sleeper, and B a portion of a rail to be secured to the sleeper by my improved rail-fastening. If desired, a suitable tie-plate C may be interposed between the tie and the rail, and the clips D are arranged to clamp the rail to the tie-plate and tie. As shown in this instance, the clips D are provided with beveled portions or faces E, which may or may not be corrugated, as desired, to coöperate with the washers F for the bolts G.

As shown in the drawings, the bolts G are arranged at an angle to each other and may

extend from a common point beneath the rail upwardly through the tie A and secure the clips D in position, as by means of the nuts H. The tie-plate C may be provided with the usual square holes through which the bolts G pass, and a suitable block or abutment I may be provided for the heads of the bolts. In this instance enlarged oval-shaped portions J are provided beneath the heads of the bolts for preventing their turning in the holes of the blocks I.

The apertures K in the clips D are made larger than the diameter of the bolts G, so that when the nuts H are loosened it will be seen that the clips D may be both vertically and laterally moved, as desired, thus permitting the rail to be adjusted vertically and laterally on the tie-plate and again secured firmly in position by tightening up the nuts H.

If desired, the tie-plate may be corrugated, as shown, and the under surfaces of the clips may also be corrugated; but a strong and secure fastening will be afforded, owing to the friction of the parts, without any corrugations.

75 Preferably the under surface of the clips D will not bear over its entire portion upon the tie-plate, as indicated in the drawings, and the clips will preferably bear against the web of the rail and upon the whole or a portion 80 of the upper surface of the base-flanges.

According to my invention it will be seen that the clips D are staggered relatively to each other longitudinally of the rail in order to carry out my construction, and the stress 85 upon the clips D constantly tends to press them inwardly and hold the rail firmly in position.

In the modification shown in Fig. 3 the bolts are shown at a different angle to that shown 90 in Fig. 2, separate bearing or abutment blocks T being provided for the heads of the bolts.

Obviously my invention may be embodied in widely-varying forms.

Therefore, without limiting myself to the 95 construction shown and described, I claim, and desire to obtain by Letters Patent, the following:

1. In a rail-fastening, the combination with the tie, of a tie-plate and a rail supported there-

- on, rail-clips for clamping the flanges of the rail to the tie and tie-plate and adapted to afford lateral support for the web of the rail, and bolts extending from a common point beneath the rail through the tie and tie-plate at an angle to each other and adjustably securing said clamps in position, whereby the rail may be adjusted laterally, substantially as set forth.
10. 2. In a rail-fastening, the combination with the rail and rail-tie, of clips extending across the flanges of the rail and abutting against the web, and bolts arranged at an angle to each other for fastening the clips loosely in holes in the clips to afford provision for horizontal adjustment and fitting tightly in the bolt-washers, the construction of the clips being such that in tightening up the bolts the horizontal component of the pressure upon the clips forces said clips inwardly and downwardly against the web of the rail, for substantially the purposes set forth.
15. 3. In a rail-fastening, the combination with the rail and rail-tie, of clips extending across the flanges of the rail and abutting against the web, and bolts extending at an angle to each other through the tie and clips for securing the clips to the tie, said clips being provided with outwardly and downwardly inclined surfaces beneath the bolt-washers, whereby the horizontal component of the pressure in tightening the bolts forces the clips inwardly and downwardly against the web of the rail, for substantially the purposes set forth.
20. 4. In a rail-fastening, the combination with the rail and rail-tie, of clips extending across the flanges of the rail and abutting against the web, and bolts arranged at an angle to each other for fastening the clips to the tie, said bolts fitting loosely in holes in the clips to afford provision for horizontal adjustment and fitting tightly in the bolt-washers, the upper surfaces of the clips and the under surfaces of the washers being corrugated, for substantially the purposes set forth.
25. 5. In a rail-fastening, the combination with the rail, tie, and tie-plate, of clips extending across the flanges of the rail and abutting against the web, and bolts for fastening the clips to the tie-plate, said clips bearing on the tie-plate over the outer portion of their under surface only, whereby the clips are forced securely down upon the rail-flanges when the bolts are tightened, for substantially the purposes set forth.
30. 6. In a rail-fastening, the combination with the rail and rail-tie, of clips extending across the flanges of the rail and abutting against the web of the rail, for substantially the purposes set forth.
35. 4. In a rail-fastening, the combination with the rail and rail-tie, of clips extending across the flanges of the rail and abutting against the web, and bolts arranged at an angle to each other through the tie and clips for securing the clips to the tie, said clips being provided with outwardly and downwardly inclined surfaces beneath the bolt-washers, whereby the horizontal component of the pressure in tightening the bolts forces the clips inwardly and downwardly against the web of the rail, for substantially the purposes set forth.

the web, and bolts extending at an angle to each other through the tie and clips for securing the clips to the tie, said clips being provided with outwardly and downwardly inclined corrugated surfaces beneath the corrugated bolt-washers, whereby the horizontal component of the pressure in tightening the bolts forces the clips inwardly and downwardly against the web of the rail, for substantially the purposes set forth.

5. In a rail-fastening, the combination with the rail and rail-tie, of clips extending across the flanges of the rail and abutting against the web, bolts arranged at an angle to each other for fastening the clips to the tie, said bolts fitting loosely in holes in the clips to afford provision for horizontal adjustment and fitting tightly in the bolt-washers, the upper surfaces of the clips and the under surfaces of the washers being corrugated, for substantially the purposes set forth.

6. In a rail-fastening, the combination with the rail, tie, and tie-plate, of clips extending across the flanges of the rail and abutting against the web, and bolts for fastening the clips to the tie-plate, said clips bearing on the tie-plate over the outer portion of their under surface only, whereby the clips are forced securely down upon the rail-flanges when the bolts are tightened, for substantially the purposes set forth.

In testimony whereof I have signed this specification in the presence of two subscribing witnesses.

GEORGE A. WEBER.
